Inventor:
Charles Harvey
by his attorney Linley May
Attnys.

UNITED STATES PATENT OFFICE.

CHARLES HARVEY, OF SOMERVILLE, MASSACHUSETTS.

CHECK OR TICKET PUNCH.

Application filed March 25, 1922. Serial No. 546,588.

To all whom it may concern:

Be it known that I, CHARLES HARVEY, a citizen of the United States, residing at Somerville, in the county of Middlesex and 5 State of Massachusetts, have invented new and useful Improvements in Check or Ticket Punches, of which the following is a specification.

This invention is embodied in certain improvements hereinafter described and claimed in a check or ticket punch of the type disclosed by the Farrow Patent, No. 1,191,680, dated July 18, 1916.

Of the accompanying drawings forming a part of this specification,—

Figure 1 is a side or edge view of a punch provided with my improvements.

Figure 2 is a perspective view of the elongated resilient strip shown by Figure 1.

Figure 3 is a perspective view of the supplemental strip shown by Figure 1.

Figure 4 is an enlarged section on line 4—4 of Figure 1.

Figure 5 is a section on line 5—5 of Figure 4.

Figure 6 is a side view of the plunger shown by Figures 1, 4 and 5.

The same reference characters indicate the same parts in all of the figures.

The punch comprises a bifurcated end portion having a check-receiving throat 12, a female die 13, plunger-guiding means provided by two orifices 14 and 15, in alignment with each other and with the female die, a looped resilient handle portion including a swinging arm 16, movable toward and from the bifurcated portion, and provided at its swinging end with an open-ended slot 17, and a plunger 18, guided by said guiding means, and formed at its outer end to cooperate with the female die in punching a check inserted in the throat 12. The plunger is provided between its ends with diametrically opposite notches 19, formed in the 45 perimeter of the plunger, without materially reducing the cross-sectional area thereof. The edges of the slot 17 loosely enter the notches 19, so that a loose connection is provided between the swinging arm 16 and the plunger, whereby swinging movements of the arm are caused to impart rectilinear movements to the plunger.

The thickness of the arm 16 is not affected by the slot 17. The loose connection provided between the plunger and the swinging

arm by the slot 17 and the notches 19, is of such nature that the strength of both the arm and the plunger at the point of connection is practically unimpaired. Said connection constitutes one of my improvements, 60 and obviates a difficulty involved by the loose connection heretofore provided. As disclosed by the Farrow patent, said connection is provided by drilling coinciding holes in the plunger and in the swinging arm, and 65 inserting a pin in the hole of the plunger. The plunger extends through an opening formed for its reception in the arm, and the pin-receiving holes in the arm intersect the plunger-receiving opening and are of larger 70 diameter than the pin. The pin is necessarily of such small diameter that its projecting ends are liable to be broken. The arm is weakened on the transverse line of the pin-receiving holes, the effective thickness 75 of the arm being reduced by said holes, so that breakage of the arm is liable to occur.

My improved slot and notch connection obviates the above-mentioned objections, 80 and is provided at less expense than the pin and hole connection shown by the Farrow patent, and enables the parts to be more quickly and conveniently assembled, as will hereinafter appear.

The preferred construction whereby the improved loose connection and the guard hereinafter described, constituting another improvement, are provided, is as follows:

The swinging arm 16 is a portion of a 90 resilient metal strip, which includes a neck portion 21, and an outer arm portion 22, extending beside the swinging inner arm portion 16, the whole forming a looped resilient handle, the compression and release of which cause swinging movements of the arm 16. The arm 22 constitutes a member of the bifurcated portion of the punch, and the female die 13 is formed by boring an orifice in the said arm near its outer end. 95 23 represents a supplemental metal strip which is secured by rivets 24 to the arm 22, and spaced from the latter by suitable means, such as a spacing layer 25, secured by the rivets. A portion of the strip 23, 100 therefore, forms one side of the check-receiving throat 12. The plunger-guiding orifice 14 is formed in this portion. The supplemental strip 23 is provided with a 105 bent extension, a portion of which forms a 110

guard 26, extending beside the entire length of the plunger at the outer side thereof, across the inner end of the plunger, and beside a portion of the plunger at the inner side thereof, as shown by Figures 1 and 5. Another portion of said bent extension forms a stop ear 27, adapted to limit the outward movement of the swinging arm 16. The guide orifice 15 is formed in the stop ear 27.

10 The described parts may be conveniently assembled by first inserting the plunger in the guide orifices 14 and 15, then moving the elongated bent strip endwise to engage the edges of the slot 17 with the plunger notches 19, and locate the female die 13 in alignment with the guide orifices, and finally securing the supplemental strip and the spacing strip to the arm 22 by the rivets 24.

15 It will be seen that the open-ended slot 17 and the plunger notches 19 enable the swinging arm 16 and the plunger to be conveniently interengaged during the assembling operation, the edges of the slot sliding into engagement with the notches.

20 25 The portion of the guard 26, which extends beside a portion of the inner side of the plunger, locates the stop ear 27 relatively near the cutting end of the plunger, and prevents the pinching; between the 30 swinging arm 16 and the stop ear 27, of the fore finger of a hand grasping the handle, the play of the arm 16 between the stop ear and the supplemental strip 23 being insufficient to permit the interposition of a 35 finger between the stop ear and the supplemental strip.

I claim:

1. A check punch comprising a bifurcated end portion having a check-receiving throat, 40 a female die, and plunger-guiding means, a looped resilient handle portion, including a swinging arm movable toward and from the bifurcated portion, a plunger guided by said guiding means, formed at its outer end 45 to cooperate with said die, and provided with diametrically opposite notches in its perimeter, the said swinging arm having in its free end an open-ended slot whose edges loosely engage said notches, so that move-

ments of the swinging arm impart rectilinear movements to the plunger. 50

2. A check punch comprising a bifurcated end portion having a check-receiving throat, a female die, and plunger-guiding means, a looped resilient handle portion, including a 55 swinging arm movable toward and from the bifurcated portion, a plunger guided by said guiding means, formed at its outer end to cooperate with said die, and provided with diametrically opposite notches in its perimeter, the said swinging arm having in its 60 free end an open-ended slot whose edges loosely engage said notches, and a bent extension on one of the members of said bifurcated portion forming a guard adapted 65 as described to prevent injury to a finger engaging the handle portion, and a stop ear adapted to limit the outward movement of the swinging arm, and constituting an element of the plunger-guiding means. 70

3. A check punch comprising an elongated resilient strip, centrally bent to form an outer and an inner arm, and a resilient handle portion carrying and permitting swinging movements of the inner arm, the 75 outer arm being provided with a female die, and the inner arm with an open-ended slot, a supplemental strip rigidly attached to the outer arm and forming therewith a bifurcated portion having a check-receiving 80 throat, said supplemental arm having a bent extension provided with two plunger guides in alignment with each other and with the female die; and a plunger movable in said 85 guides, formed to cooperate with the female die, and provided with diametrically opposite notches in its perimeter, loosely engaging the edges in said slot, said extension including a guard portion, adapted as described to prevent injury to a finger engaging the handle portion, a stop portion or ear, adapted to limit the outward movement 90 of the swinging arm, and constituting one of said plunger guides.

In testimony whereof I have affixed my 95 signature.

CHARLES HARVEY.
